UNITED STATES PATENT OFFICE.

WILLIAM A. FINDLEY, OF SAN FRANCISCO, CALIFORNIA.

TOOL.

1,351,947.

Specification of Letters Patent.

Patented Sept. 7, 1920.

Application filed November 18, 1919. Serial No. 338,970.

To all whom it may concern:

Be it known that I, WILLIAM A. FINDLEY, a citizen of the United States, residing in the city and county of San Francisco and 5 State of California, have invented a certain new and useful Improvement in Tools, of which the following is a specification.

My invention relates to improvements in tools of the class used for beveling, expanding and bending the ends of boiler tubes into boiler heads wherein a reciprocating hammer is provided with a plurality of shoulders adapted to successively bevel, expand and bead the end of a boiler tube and operates 10 in conjunction with means for holding said hammer to the work.

The primary object of the present invention is to provide improved means for successively beveling, expanding and beading 15 the ends of the boiler tubes and the like.

A further object of the present invention is to provide a new and improved tool adapted to bevel, expand and bead the ends of the boiler tubes and the like.

25 Another object of the present invention is to provide an improved tool adapted to be reciprocated by a pneumatic hammer or the like and having a plurality of shoulders by means of which, when used successively, boiler tubes may be effectively secured within 30 in a boiler head.

A still further object of the present invention is to provide an improved tool of the character described having means for holding 35 the said tool up to the work being performed.

It is a still further object to provide an improved reciprocating tool of the character described having improved means for 40 normally preventing the rotation of said tool whereby the proper shoulder may be held to the work and thereby prevent mar- ring of the end of said tube.

I accomplish these several objects by 45 means of the improved device disclosed in the drawings forming a part of the present specification wherein like characters of reference are used to designate similar parts throughout the said specifications and drawings, and in which:

Figure 1 is a broken sectional view of a portion of a tube and boiler head disclosing the application of my improved tool during the beveling process;

55 Fig. 2 is a similar view disclosing the

position of the tool during the expanding process;

Fig. 3 is also a similar view disclosing the position of the tool during the beading process;

Fig. 4 is an end elevation of Fig. 1; and

Fig. 5 is a transverse sectional view on line 5—5 of Fig. 1 in the direction indicated, disclosing the opposite end of the tool from that disclosed in Fig. 4.

Referring to the drawings the numeral 1 is used to designate a core having a longitudinally disposed bore 2 opening on one side thereof. The core 1 is also provided on one end thereof with a flat longitudinally 70 disposed surface 3 having an arcuate groove 4 therein, said groove 4 having an enlarged portion 6 the purpose of which will herein- 75 after be more fully described.

A latch or lug 7 is pivotally mounted upon 75 the core 1 as at 8 and is provided with an extension 9 bearing against a longitudinally disposed spring 11 secured to the core 1 and having a lateral extension 12 extending into the longitudinal bore 2 of said core 1. 80 When the core 1 is inserted within the end of the tube 14 the lug 7 engages the outer surface of a boiler head or plate 16 and thereby presents a resilient resistance to a longitudinal movement of the core 1 within 85 the tube 14.

Slidably and rotatably mounted within the bore 2 of the core 1, and with the inner end thereof resting against the extension 12 of the spring 11 is a reciprocating hammer 90 17 having an enlarged portion 15 provided with a beveling shoulder 18, an expanding shoulder 19 and a beading shoulder or extension 20 all arranged in substantially the same place, the hammer 17 is also provided 95 with a hexagonal extension 21 adapted to be engaged by a pneumatic hammer or the like not shown.

The enlarged portion 15 is also provided 100 with beveled lugs 22 which normally engage the flat surface 3 of the core 1 while the intermediate portions of said enlarged portion 15 slidably engages the groove 4 adjacent said flat surface 3. By moving the enlarged portion 15 of the hammer 17 opposite 105 the enlarged portion 6 of the groove 4 the hammer 17 may be rotated, moving one of said lugs 22 through said enlarged portion 6 until the required shoulder is in position to engage the end of the tube 14. 110

In order to hold the core 1 with the hammer 17 adjacent the interior wall of the tube 14, or "up to the work" as it is commonly expressed, an arcuate resilient shim 24 is detachably mounted upon the core 1 and diametrically opposite the bore 2 therein.

By means of this novel arrangement the shim 24 may be removed and a larger shim 10 attached to readily and easily accommodate one core to various sizes of tubes.

In operation the core 1 is first inserted within the tube 14 until the latch 7 rests against the adjacent boiler head or plate 16 and the hammer 17 is turned to bring the shoulder 18 adjacent the end of the tube 14. By means of a pneumatic hammer, not shown, the hammer 17 is rapidly reciprocated longitudinally thereby actuating the hammer 17 and shoulder 18 thereof to deliver sharp rapid blows onto the projecting end of the tube 14 which will bevel or flare the end of said tube as disclosed in Figs. 1 and 4 of the drawings. The core 1 is turned 25 or rotated upon its axis until the entire periphery of the tube 14 has been properly beveled. During such rotation the hammer 17 is prevented from rotating, thereby retaining the shoulder 18 up to the work, by 30 means of the beveled sides of the lugs 15 slidably engaging the flat surfaces 3 on each side of the groove 4 of the core 1 as disclosed in Fig. 4 of the drawings.

After the entire periphery or circumference of the end of the tube 14 has been properly beveled the hammer 17 is moved outwardly and longitudinally within its bore 2 until the lugs 22 on the enlarged portion 15 are opposite the enlarged portion 6 of the 35 groove 4. The hammer 17 is then rotated, the lugs 22 passing through said enlarged portion 6 of the groove 4 till the next shoulder 19 extends laterally from the core 1 and opposite the beveled end of the tube 14. The hammer 17 is then again reciprocated rapidly by the pneumatic hammer and the core 1 rotated as before and the beveled edge of the tube is laid flat upon the boiler head or plate 16 as disclosed in Fig. 2 of the drawings. This process, by hammering, 45 forges or swages portions of the molecules in the end of the tube 14 backwardly into said tube and causes the same to expand and thereby entirely and securely fill the tube 50 aperture within said boiler head or plate 16, the core 1 and hammer 17 being meanwhile held up to the work by means of the resilient arcuate shim 24.

The hammer 17 is then again moved longitudinally to bring the lugs 22 opposite the enlarged portions 6 of the groove 4 and then rotated to bring the beading shoulder 20 adjacent the end of the tube as disclosed in Fig. 3 of the drawings. The hammering 55 process is again repeated and the bead there-

by formed upon the end of the tube 14 thereby completing the process.

During the hammering process with any one of the shoulders the hammer 17 is moved longitudinally against the tension of the extension 12 of the spring 11 so that as soon as the impact has been delivered the said spring 12 will move the hammer 17 away from the work and thereby permitting successive movements or impacts of said 75 shoulder against the end of the tube.

The spring 11 also permits a slight longitudinal movement of the core 1 longitudinally within the tube 14 thereby preventing the impact from being delivered onto the 80 core 1 after the shoulders have become slightly shortened through wear or usage.

In order to prevent entire withdrawal longitudinally of the hammer 17 I have provided a retaining latch 26 which engages the hexagonal end 21 of the said hammer, said latch 26 being used as a pivot as at 8 to retain the lugs 7 in pivotal connection with the core 1. By spreading the ends of said member or latch 26 said ends may be 90 disconnected from said core 1 and thereby permit withdrawal of the hammer 17.

Having thus described my invention, what I claim as new and desire to secure by Letters Patent is:

1. A tool of the character described comprising a slidable and rotative hammer having a plurality of shoulders thereon adapted to successively bevel, expand and bead the end of a tube onto a boiler head or the like; 100 and a core having a bore on one side thereof to slidably and rotatably hold said hammer within said tube and adjacent the internal wall thereof.

2. A tool of the character described comprising a slidable and rotative hammer having a plurality of shoulders thereon adapted to successively bevel, expand and bead the end of a tube onto a boiler head or the like; a core having a bore on one side thereof to 110 slidably and rotatably hold said hammer within said tube and adjacent the internal wall thereof; and means for resiliently compressing said core against one portion of the internal wall of the tube to hold said hammer adjacent said internal wall.

3. A tool of the character described comprising a slidable and rotative hammer having a plurality of shoulders thereon adapted to successively bevel, expand and bead the 120 end of a tube onto a boiler head or the like; a core having a bore on one side thereof to slidably and rotatably hold said hammer within said tube and adjacent the internal wall thereof; and a resilient shim detachably connected to the core for resiliently compressing and holding the same and hammer therein adjacent a portion of the interior wall of said tube.

4. A tool of the character described com- 130

prising a slidable and rotative hammer having a plurality of shoulders thereon adapted to successively bevel, expand and bead the end of a tube onto a boiler head or the like; 5 a core having a bore on one side thereof to slidably and rotatably hold said hammer within said tube and adjacent the internal wall thereof; and a resilient shim detachably connected to the core and adapted to engage one portion of the interior wall of 10 the tube and retain the core and hammer therein against the opposite wall of said tube.

5. A tool of the character described comprising a core adapted for insertion within the end of a tube or the like and having a longitudinally disposed bore opening on one side of said core; a hammer adapted for engagement with a pneumatic hammer or the 15 like, rotatably and slidably mounted within said bore and having a plurality of shoulders adapted to successively bevel, expand and bead the end of said tube when reciprocated by said pneumatic hammer; and means for 20 normally unseating the shoulders of the hammer from the end of the tube when said core is in operative position within said tube.

6. A tool of the character described comprising a core adapted for insertion within the end of a tube or the like and having a longitudinally disposed bore opening on one side of said core; a hammer adapted for engagement with a pneumatic hammer or the like, rotatably and slidably mounted within 30 said core and having a plurality of shoulders adapted to successively bevel, expand and bead the end of said tube when reciprocated by said pneumatic hammer; means for normally unseating the shoulders of the hammer 35 from the end of the tube when said core is in operative position within said tube; and resilient means for normally holding the core with the hammer adjacent the interior wall 40 of the tube.

45 7. A tool of the character described comprising a core adapted for insertion within the end of a tube or the like and having a longitudinally disposed bore opening on one side of said core; a hammer adapted for engagement with a pneumatic hammer or the like, rotatably and slidably mounted within 50 said bore and having a plurality of shoulders adapted to successively bevel, expand and bead the end of said tube when reciprocated by said pneumatic hammer; means for nor-

mally unseating the shoulders of the hammer from the end of the tube when said core is in an operative position within said tube; and a resilient shim detachably connected to the core and adapted to normally retain said core and hammer therein adjacent interior wall of said tube.

8. A tool of the character described comprising a slidable and rotative hammer having a plurality of shoulders thereon adapted to successively bevel, expand and bead the end of a tube onto a boiler head or the like; a core having a bore on one side thereof to slidably and rotatably hold said hammer within said tube and adjacent the internal wall thereof; and resilient means for preventing a longitudinal movement of the core into the tube when the hammer is reciprocated.

9. A tool of the character described comprising a slidable and rotative hammer having a plurality of shoulders thereon adapted to successively bevel, expand and bead the end of a tube onto a boiler head or the like; a core having a bore on one side thereof to slidably and rotatably hold said hammer within said tube and adjacent the internal wall thereof; and means for preventing withdrawal of the hammer from the core.

10. A tool of the character described comprising a core adapted for insertion within the end of a tube or the like and having a longitudinally disposed bore opening on one side of said core; a hammer adapted for engagement with a pneumatic hammer or the like, rotatably and slidably mounted within said bore and having a plurality of shoulders adapted to successively bevel, expand and bead the end of said tube when reciprocated by said pneumatic hammer; means for normally unseating the shoulders of the hammer from the end of the tube when said core is in an operative position within said tube; a resilient shim detachably connected to the core and adapted to normally retain said core and hammer therein adjacent the interior wall of said tube; and means formed integral with the core for engaging the hammer to prevent rotation thereof within the bore while being reciprocated by the pneumatic hammer.

In witness whereof I hereunto set my signature.

WILLIAM A. FINDLEY.
